(57) **CLAIM**

The ornamental design for an ergonomic game interface device with LEDs, as shown and described.

DESCRIPTION

The following co-pending design patent applications are related to this application: U.S. design patent application number U.S. design patent application Ser. No. 29/259,349 entitled "Controller with Infared Port", filed on May 6, 2006; U.S. design patent application Ser. No. 29/259,350 entitled "Controller with Tracking Sensor", filed on May 6, 2006; U.S. design patent Appl. No 29/259/348 entitled "Tracked Controller Device", filed on May 6, 2006; U.S. Appl. No. 29/246,744, entitled "Video Game Controller Front Face" filed on May 8, 2006; U.S. design application Ser. No. 29/246,743, entitled "Video Game Controller", filed on May 8, 2006; U.S. design patent application Ser. No. 29/246,767 entitled "Video Game Controller", filed on May 8, 2006; U.S. design patent application No. 29/246,768 entitled "Video Game Controller", filed on May 8, 2006; U.S. design patent application No. 29/246,763 entitled "Ergonomic Game Controller Device with LEDS and Optical Ports", filed on May 8, 2006; U.S. design patent application No. 29/246,759 entitled "Game Controller Device with LEDS and Optical Ports", filed on May 8, 2006; U.S. design patent application No. 29/246,765 entitled "Design for Optical Game Controller Interface", filed on May 8, 2006; U.S. design patent application No. 29/246,766 entitled "Dual Grip Game Control Device with LEDS and Optical Ports", filed on May 8, 2006; U.S. design patent application No. 29/246,765 entitled "Game Interface Device with LEDS Optical Ports", filed on May 8, 2006.

The sole FIGURE is a front elevational view of an ergonomic game interface device with LEDs showing our new design.

Certain portions of the single figure are reflected as a phantom dotted line. Said portion of the figure are not a part of the presently claimed design but may otherwise be helpful to understanding the environment in which the claimed design is associated.
